UNITED STATES PATENT OFFICE.

THOMAS CAREY AND LEN SCHABLOSKE, OF CHICAGO, ILLINOIS.

HEATING MECHANISM FOR KILNS.

1,115,171.

Specification of Letters Patent. Patented Oct. 27, 1914.

Application filed February 19, 1913. Serial No. 749,500.

To all whom it may concern:

Be it known that we, THOMAS CAREY and LEN SCHABLOSKE, citizens of the United States, residing at Chicago, county of Cook, 5 and State of Illinois, have invented a new and useful Improvement in Heating Mechanisms for Kilns, of which the following is a specification.

Our invention relates to heating mechanism and arrangement for kilns, particularly for kilns in which ceramic products such as bricks, building blocks, tile, etc., are fired.

Wood and coal have been used as fuel but 15 with more or less inefficiency as considerable time was necessary and the heat distribution was not always uniform and there was considerable waste. As wood and coal became expensive, oil came into use as the 20 fuel, but now oil is also becoming more costly and the market price is so fluctuating, the price sometimes going up so high that its use as fuel in the ordinary manner would be prohibitive from a business stand- 25 point.

The general object of our invention is to provide heating mechanism which can utilize coal or wood as a fuel much more efficiently than has heretofore been possible. 30 This we accomplish by providing improved grate mechanism; by forcing the draft with steam, preferably superheated, and air; by blowing air and steam under considerable pressure below grate level to distribute the 35 heat from the fire to the bricks or other products at and near the bottom of the kiln; and by blowing air and steam, preferably superheated, into the kiln above grate level so that heat is uniformly distributed 40 throughout the interior of the kiln. Improved superheating mechanism and steam and air flow controlling mechanisms are provided. The various mechanisms are grouped into heating units which can be 45 readily moved and carried from one kiln to another.

In the drawings which illustrate the various features of the invention, Figure 1 is a perspective view of the corner of a kiln 50 showing a heating unit in operative position; Fig. 2 is a side elevational view of the kiln with the right end thereof in section on a vertical median plane; Fig. 3 is an enlarged view, partly in section, of an inspirator, and Fig. 4 is a perspective view of a nozzle.

The products to be fired, such as brick, are built up as usual to form a pile 5 in which one or more archways 6 are provided in the usual manner. In the ends of the archways 60 the grates 7 are set up. The grate which we use has hollow grate bars communicating at their front ends with hollow head 8 and secured at their rear ends to head 9. To support the grate at its front end we utilize 65 an arch frame 10 having ledges 11 and 12 on its opposite inner sides for supporting a cross beam 13 on which the front end of the grate rests. At the rear end of the grate a cross beam 14 receives the grate bars and at 70 its ends rests on the brickwork at the sides of the archway 6. The arch frame 10 may be within the archway, or in front thereof, or partly within and partly outside. Pivot lugs 15 on one side of the arch frame serve 75 to support a door 16, and the other side has a detent extension 17 for locking the door, the door having draft openings 18. The arch frame by overhanging the front part of the grate is highly heated by the fire on 80 the grate and is hollow and included in a steam circuit so that the steam may be highly superheated.

A main pipe 19 supplies steam for the various heating outfits. A branch pipe 20 85 leads from the main pipe to the front head of the grate and includes controlling valves 21 and 22 at the main pipe and head respectively, the hollow grate bars having upwardly opening outlets 23. Inserted in 90 pipe 20 between valve 22 and the outer grate head is an inspirator 24 having air inlets 25 (see Fig. 3), the steam flowing from nozzle 26 taking up air through these inlets so that air and steam are forced from 95 the grate outlets 23 into and through the burning mass of wood or coal on the grate, thus producing a very hot fire. A branch pipe 27 leads from pipe 20 to the blast nozzle 28 pointing into the archway 6 below the 100 grate. A valve 29 controls the flow through pipe 27 and between the valve and the blast nozzle is inserted an air inspirator 30. Steam and air may thus be blown into the archway below the grate to carry heat to 105 the center of the kiln and particularly to the lower courses thereof. Another pipe 31 leads from the main pipe 19 to a multiple outlet nozzle 32 disposed in the archway above the grate so that steam may be blown 110 toward the center of the kiln to create circulation of heat from the grate uniformly

throughout the kiln and to prevent the heat from accumulating directly above the grate and becoming too intense. The flow through pipe 31 is controlled by valves 33 and 33', and an air inspirator 34 may be inserted between valve 33' and the nozzle 32.

A pipe 35 connects pipe 31 with the inlet 36 of the hollow arch frame 10 and is controlled by valve 37. Another pipe 38 connects the outlet 39 of the arch frame with the pipe 27 at a point between valve 29 and inspirator 30, a valve 40 controlling pipe 38. By adjusting the various valves either normal steam or superheated steam may be caused to flow through the various pipes. If it is desired to use only normal steam, valves 37 and 40 are closed. If superheated steam flow to the grate and to nozzle 28 is desired, valves 37 and 40 are opened and valve 21 closed. The flow will then be from main 19, through pipes 31 and 35, arch frame 10, pipe 38, and pipe 27, part of the superheated steam then flowing through inspirator 30 and nozzle 28, and the remainder flowing through pipe 20 and inspirator 24 to the grate. If superheated steam flow to nozzle 32 is desired, valves 37 and 40 are opened and valve 33 closed, steam then flowing from main pipe 19, through pipe 20, arch frame 10, pipe 35, and pipe 31 to nozzle 32, the steam being highly superheated in the hot arch frame. By adjusting the corresponding valves, steam flow may be cut off from the nozzles, or the grate, or the arch frame, as desired, in order to get the best and most efficient results. By forcing the fire with steam, or steam and air, and then preventing localization of the heat and causing rapid and uniform distribution thereof throughout the kiln, firing can be accomplished in much shorter time and with greater efficiency and less expense than in the old systems using wood or coal for fuel.

It will be noted that the grate outlets 45 23 increase in size in proportion to their distance from the inlet end of head 8 in order that friction may be compensated for and the outflow of steam and air may be uniform. The arch frame 10 has a drain outlet 50 41 for water of condensation.

We do not desire to be limited to the precise construction, arrangement and operation described, as changes and modifications are no doubt possible which would still come 55 within the scope of the invention, and

We claim the following:

1. In heating mechanism for kilns, the combination of a hollow arch frame applied at the entrance of the usual archway in the kiln, a hollow grate supported on said arch frame and having blast outlets in the fire thereon, means for supplying steam to said hollow arch frame to be superheated by the heat from said fire, and a connection for leading the superheated steam to said grate. 60

2. In heating mechanism for kilns, the combination of a hollow arch frame applied at the entrance of the usual archway in the kiln, a hollow grate supported on said arch frame and having blast outlets in the fire thereon, means for supplying steam to said hollow arch frame to be superheated by the heat from said fire, a nozzle pointing into said archway below the grate and controllable connections between said arch frame 70 and said grate and nozzle for conveying the superheated steam.

3. In heating mechanism for kilns, the combination of a hollow arch frame applied at the entrance of the usual archway in the kiln, a hollow grate supported on said arch frame and having blast outlets in the fire thereon, means for supplying steam to said hollow arch frame to be superheated by the heat from said fire, a connection for leading 80 the superheated steam to said grate, and an air inspirator included in said connection to admit air to the steam.

4. In heating mechanism for kilns, the combination of a hollow arch frame applied 90 at the entrance of the usual archway in the kiln, a hollow grate supported on said arch frame and having blast outlets in the fire thereon, means for supplying steam to said hollow arch frame to be superheated by the 95 heat from said fire, a nozzle pointing into said archway below the grate and controllable connections between said arch frame and said grate and nozzle for conveying the superheated steam, and air inspirators included in said connections to admit air to the superheated steam. 100

In testimony whereof we have signed our names to this specification in the presence of two subscribing witnesses this 29th day of January, A. D. 1913, at Chicago, Illinois.
